ARTICLE HANDLING APPARATUS

Donald H. Mitchell, Cranford, N. J., assignor to
Western Electric Company, Incorporated, New
York, N. Y., a corporation of New York

Application December 7, 1943, Serial No. 513,311

2 Claims. (Cl. 29—288)

This invention relates to article handling apparatus, and more particularly to apparatus for supporting articles in various positions during assembly.

An object of the invention is to provide a simple, efficient and practical article handling apparatus.

With this and other objects in view, the invention comprises a support for an article pivotally carried by a base and adapted to be located at varied angular positions relative to the base through the control of a treadle-actuated element and a locating member movable with the support.

Other objects and advantages will be apparent from the following detailed description when considered in conjunction with the accompanying drawing, wherein:

Fig. 1 is a side elevational view of the apparatus; and

Fig. 2 is an end elevational view of the apparatus.

Referring now to the drawing, a base is indicated generally at 10 and is composed of sides 11 and 12, which are triangular in general contour, formed of metal angles and secured at their spaced positions by transverse angle members 14. Journal members 15 are mounted upon the upper pivotally mounted upon the shaft 16. The support the ends of a shaft 16.

A supporting unit, indicated generally at 18, is pivotally mounted upon the shaft 16. The support 18 includes an outer frame composed of spaced channel members 19 rigidly connected at their spaced positions by transverse angle members 20 and 21, the latter being secured by suitable means, such as welding, to the under surfaces of the channel members. Thus there is included an outer frame with spaced longitudinal channel members connected rigidly to the angle members 20 and 21. The outer frame carries bearing members 22 for pivotal connection with the shaft 16. Within this frame, and normally resting upon the angle members 20 and 21, is an inner frame including channel members 23. The channel members 23 are connected at their spaced positions by a metallic plate 24 intermediate the ends of the channel members and a similar metallic plate 25 at one end thereof, the opposite ends of the channel members being connected by a metal angle 26. The plates 24 and 25 extend beyond the sides of the channel members 23 and over the channel members 19 of the outer frame, to rest thereon if so desired. The inner and outer frames are pivotally connected to each other

through the aid of a shaft 28. Apertured blocks or journalled members 29 are disposed in the channel members 19, as illustrated in Fig. 1, and are secured in place by suitable means such as welding. Similar members, which may be termed bearing members, 30, apertured to receive the shaft 28, are disposed in the channel members 23 and are secured in place by suitable means such as welding. It will, therefore, be apparent that the outer frame is hollow and adapted to receive the inner frame therein, to which it is pivotally connected through the aid of the shaft 28.

At the opposite end of the outer frame, adjusting screws 32 are carried by the angle member 20, and, through the aid of lock nuts 33, the adjusting screws may be varied relative to the plate 25 to adjust the inner frame to a true horizontal position with respect to the base 10. If the floor upon which the base 10 rests is in a true horizontal plane, the adjusting screws would not be needed, as the frames in their zero or normal positions are parallel with the bottom of the base.

The inner frame includes article supporting elements 34 and 35 mounted upon the plates 24 and 25 respectively, and formed with arcuate article supporting surfaces 36, as shown. A retaining band 37 is provided for each of the elements 34 and 35 and has one end fixed to one side of its respective element, the other end being provided with a loop 38 to form connection with a retaining screw 39, a wing nut 40 of which is adapted for engagement with a clamping bracket 41 for securing an article or unit 42 in place. The bracket 41 is grooved or slotted to removably receive the screw 39, this bracket being rigidly mounted upon its respective element 34 or 35. Locating pins 44 are carried by the element 34 and are receivable in hollow portions of the article 42, to assist in locating the article on the supporting elements. Locating elements 45, of the contours shown in Fig. 2, are mounted upon the angle members 26 and serve to locate the article 42 in the elements 34 and 35.

Through the pivotal connection of the inner and outer frames at the shaft 28, it is possible to move the article 42 from the assembling position shown to a vertical or loading position, where it may be removed from the apparatus. Means is, therefore, provided to hold the inner frame in a given assembling position with respect to the outer frame and to also support the inner frame with the article in a vertical position and against accidental displacement from this position. This means includes retaining elements 48, which are

mounted one upon each side of the supporting unit 18.

Considering the illustration in Fig. 1, a pivot block 40 is mounted in the adjacent channel member 19 to pivotally support, at 50, the element 48. The element 48 is provided with an elongate aperture or slot 51, with an offset portion 52 at its free end providing a pocket or recess 53 to receive a retaining screw 54, the latter being carried by the element 34 and supporting a washer 55. When it is desirable to move the article into a vertical position, this may be accomplished by moving the inner frame with the article about the shaft 28. During this movement of the inner frame, the elements 48 will be moved about their pivots 50 until the screws 54 are disposed in the recesses 53 to thus hold the frame and article against accidental return movement to the horizontal position.

The article or unit 42 during the assembling thereof may be moved into any desired angular position with respect to the true horizontal position. This is accomplished through a treadle-actuated element indicated generally at 57, and locating elements or members 58. Considering first the locating elements 58, it will be understood that there are two such elements supported by triangular brackets 59, the latter being fixed to the under surfaces of the channel members 19 by any suitable means such as welding. The elements 58 are identical in structure and a description of the one illustrated in Fig. 1 will apply to both elements.

Considering now the element 58 of Fig. 1, it will be noted that a plurality of recesses 60 in one surface thereof provides locating portions, including in each, companion cam surfaces 61. The recesses or locating positions are separately identified by the central or zero (0°) position and the five degree (5°), ten degree (10°) and fifteen degree (15°) locating positions upon each side of the zero position. Hook-shaped portions 64 and 65 are located at the respective ends of the locating recesses, to limit the possible movement of the unit 18 with the article in either direction.

The element 57 includes a rod 70 carried by the upper ends of a plurality of angle members 71 and extending through apertures therein. The angle members 71 are secured to a transverse member 72 by suitable means, such as welding, thus holding all of the angle members at their spaced positions and for movement as a unit about a shaft 73 upon which they are mounted. The ends of the shaft 73 are supported in bearings 74 mounted upon the sides 11 and 12 of the base 10. Treadle portions 76, secured to the inner pair of angle members 71 by suitable means such as welding, are of the general contour illustrated in Fig. 1, and have a transverse member 77 fixed thereto to complete the treadle portion of the element 57. Suitable means such as a spring 79, having one end fixed, as at 80, to the element 57 and the other end fixed, as at 81, to the base 10, normally urges the element 57 counterclockwise about the axis of the shaft 73.

Considering now the operation of the apparatus, let it be assumed that the various parts of the apparatus except the retaining bands 37 and their respective retaining screws 39 are in the position shown in the drawing, the bands and screws being moved to one side to allow for the positioning of an article 42 in place. Through the aid of pins 44 and the locating elements 45, the article is disposed in the position shown. The article may be a cylindrical casing in which vari-

ous other structures (not shown) may be mounted. Due to the fact that, at the present time, the article or unit 42 is classified as secret under government regulation, its detailed structure cannot be defined and the effect of the apparatus thereon during its assembly cannot be defined. During the assembly of the article it is desirable to tilt the article, namely the cylindrical casing, into various angular positions with respect to the base or with respect to a true horizontal position. It is, therefore, necessary that the article or casing be held against accidental displacement. The bands 37 are, therefore, passed about the article, and through the aid of the screws 39 and their wing nuts 40 tightened against the brackets 41, the article 42 is firmly secured in a desired location on the apparatus. If the apparatus should be moved from one position to another, it is important that when the rod 70 of the element 57 is in the recess 60 of the zero position of the locating element 58, that the center line of the article be in a true horizontal position. This may be brought about through adjustment of the screws 32. However, once this location has been determined, it need not be checked thereafter for subsequent operations of the apparatus. During this adjustment, of course, there is caused a variation between the positions of the inner and outer frames of the supporting unit 18 about the shaft 28.

With the apparatus in the position shown, let it be assumed that it is desirable to tilt the apparatus clockwise ten degrees (10°). This is made possible by moving the unit 18 with the article a short distance counterclockwise about the shaft 16 until the rod 70 is free of the recess 60 at the zero position, after which the element 57 may be moved about its pivot or shaft 73 through the aid of the treadle 76-77. The unit 18 with the article may then be moved clockwise until the recess 60 for the ten degree (10°) position registers with the rod 70, after which the treadle may be released, allowing the force of the spring 79 to move the rod 70 into the recess 60 at this position. The companion cams 61 of this recess cooperate with the rod 70 to automatically locate the unit 18 at the desired angle. Regardless of which cam surface the rod engages first, this surface will cause the rod to find its position in engagement with the other companion cam surface also. In following this same procedure, either one of the positions above the zero position may be brought into registration with the rod 70 of the element 57, the end portion 65 limiting the clockwise movement of the unit 18 with the article, it being adapted to engage the rod 70 should the operator accidentally release the unit 18 before it is located in the desired position. In a similar manner any one of the locations beneath the zero positions may be brought into registration with the rod 70 to locate the element 18 at any one of varied angular positions counterclockwise of the zero or true horizontal position.

After the article or unit has been completed and it is desirable to remove it from the apparatus, the article may be moved into vertical position by moving the inner frame, including the channel members 23 and their article supporting elements 34 and 35, about the shaft 28. During this movement the screws 54 move upwardly in their respective apertures 51 and are located in the recesses 53, where they hold the inner frame with the article against accidental return movement during freeing of the article from the inner

frame. The article may be released by loosening the wing nuts 40 a suitable distance to free the retaining screws 39 from their brackets 41 so that they, together with the retaining bands 37, may be moved free of the article. After the completed article has been removed, the inner frame may be returned to the horizontal position, where it will lie within the outer frame with the extended portions of the plates 24 and 25 resting upon the channel members 19 of the outer frame, or where the plate 25 will rest upon the adjusting screws 32 of the outer frame. The apparatus is now ready to receive another article 42 and through the aid of the element 57 and the locating member 58, this article may be adjusted into varied angular positions with respect to the base about the pivot or shaft 16.

Although specific improvements of the invention have been shown and described, it will be understood that they are but illustrative and that various modifications may be made therein without departing from the scope and spirit of this invention as defined by the appended claims.

What is claimed is:

1. An article handling apparatus comprising a base, a unit for supporting an article, pivotal means connecting the unit to the base at an off-center position adjacent the under side of the unit, a locating member rigidly secured to the underside of the unit at the longest portion thereof from the pivotal means and including recesses formed of angularly disposed cam surface, an

element pivotally carried by the base and having a projection receivable in any of the recesses and selectively guided therein singly by the respective cam surfaces to cooperate with the locating member, and the pivotal means to support the unit at varied angular positions relative to the base, means actuatable to move the element away from the locating member, and means to normally urge the element toward the locating member.

2. An article handling apparatus comprising a base, a supporting unit having interfitting members, bearings at the upper extremity of the base, a shaft having its ends journaled in the bearings and extending laterally of the unit to pivotally connect one of the members to the base, means carried by the other member to support an article, a shaft parallel with the first mentioned shaft extending through the adjacent ends of the members to pivotally connect them for movement of the article supporting member into a position parallel with or at right angles to the base supported member, an arm pivotally carried by the base supported member and formed for connection with the article supporting member in either position, means cooperating with the arm to secure the article supporting member in either position, and means for locating the unit about its supporting shaft with the article in varied angular positions relative to the base.

DONALD H. MITCHELL.
